Assistant Examiner—Mitchell I. Siegel
Attorney, Agent, or Firm—Dick and Harris

[73] Assignee: **Video Technology Industries, Inc.**,
Wheeling, Ill.

CLAIM

[**] Term: 14 Years

The ornamental design for an electronic toy audio amplifier and sound effects housing, as shown and described.

[21] Appl. No.: 606,335

DESCRIPTION

[22] Filed: Oct. 30, 1990

[52] U.S. Cl. D21/113; D14/168;
D14/173

[58] Field of Search D14/100, 129, 154, 160,
D14/165, 168, 173, 188, 196, 226, 246, 299;
D21/111-113; 434/201

FIG. 1 is a front perspective view of the electronic toy audio amplifier and sound effects housing, showing our my design;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.
